CLAIM

I claim the ornamental design for an operation control device for driving robot, as shown and described.

DESCRIPTION

FIG. 1 is a front view of the claimed design;

FIG. 2 is a rear view of the claimed design of FIG. 1;

FIG. 3 is a right side view of the claimed design of FIG. 1;

FIG. 4 is a left side view of the claimed design of FIG. 1;

FIG. 5 is an enlarged detail view of a portion of the claimed design of FIG. 1, the detail view being taken from the left side of the claimed design as shown in FIG. 4;

FIG. 6 is a top view of the claimed design of FIG. 1;

FIG. 7 is a bottom view of the claimed design of FIG. 1;

FIG. 8 is a front right perspective of the claimed design of FIG. 1; and,

FIG. 9 is a front left perspective of the claimed design of FIG. 1.

The broken lines in the drawings illustrate portions of the operation control device for driving robot that represent environment of the claimed design and forms no part of the claimed design.
